UNITED STATES PATENT OFFICE.

EMANUEL INGHAM, OF WASHINGTON, DISTRICT OF COLUMBIA.

RADIO MAST HOLDER.

Application filed April 16, 1924. Serial No. 706,861.

This invention relates to staff or mast holders and particularly to a device whereby a mast suitable for use for supporting a radio aerial may be mounted upon an ordinary chimney.

The general object of the invention is to provide a strong, fireproof, and substantially storm proof device which may be readily attached to the top of any of the ordinary 10 styles of existing chimneys without in any way mutilating the same, and which will rigidly and permanently support a radio mast. Further and more specific objects will hereinafter appear.

15 In order that the invention may be readily understood, reference is had to the accompanying drawings, forming part of this specification and illustrating several embodiments of the invention. In these drawings:

20 Figure 1 is a plan view of one form of an improved supporting bracket which I have devised;

Figure 2 is a side elevation thereof;

25 Figure 3 is a plan view of a second or auxiliary bracket which I employ in connection with that shown in Figures 1 and 2;

Figure 4 is a side elevation thereof;

30 Figure 5 is a vertical sectional view showing a chimney with a mast mounted therein and supported by the two brackets illustrated in Figures 1 to 4;

35 Figure 5^a is a fragmentary sectional detail similar to Figure 5, but showing a slightly modified construction;

Figures 6 and 7 are plan and side views 40 respectively of a simplified form of supporting bracket which may be employed in some cases;

Figure 8 is a plan view similar to Figure 1, but showing a bracket so constructed as to support the mast on the outside of a chimney;

Figure 9 is a side elevation thereof;

45 Figure 10 is a plan view, partly in section showing an auxiliary bracket designed to be employed in connection with the bracket shown in Figures 8 and 9, the chimney being indicated by dotted lines;

50 Figure 11 is a plan view of a still different construction of supporting bracket which is adapted to encircle a chimney;

Figure 12 is a side elevation showing a mast supported on a chimney by means of the bracket illustrated in Figure 11 and an auxiliary or lower bracket, the chimney being indicated in dotted lines, and

Figure 13 is a plan view showing the lower or auxiliary bracket appearing in Figure 12, the mast being shown in section.

Referring to the drawings in detail, and more particularly to Figures 1 to 5, a chimney is designated by the letter X, and a staff or mast, preferably formed of iron pipe, and of suitable height, is shown at C. This mast is supported within the chimney flue by 65 means of a pair of independent brackets of special construction designated in their entirety by the characters A and B, respectively.

The main or upper bracket A, as shown in 70 Figure 1, comprises four sections designated a, b, c, and d, each section comprising two portions or arms disposed at right angles to each other, so that the sections when assembled form a rectangular frame. In cross-section, this frame is of the shape of an angle iron and comprises a horizontal member or flange 1 and a vertical member or flange 2. Each section is provided at one end with an offset extension 3, slotted as indicated at 4 in Figure 1, and adapted to receive a bolt 5 passing loosely through the slot and set into the underlying section. By virtue of this construction the bracket or frame as a whole is expandable and may be 80 adjusted to different sizes so as to accommodate itself to the variations in the sizes of the flue openings into which it is to be fitted. After the sections have been properly adjusted to the desired size they may be 85 clamped together by tightening up the bolts 5, as will be obvious.

One or more of the sections of the bracket or frame carries a mast receiving socket 6 provided with a set screw 7, such socket 95 preferably being located at the corner of the angular section. As shown in Figure 1, both the sections a and c are shown as provided with mast receiving sockets, so that two masts may be supported by a single bracket, but 100 ordinarily, in the majority of cases, only one mast is required and therefore only a single socket is provided.

In addition to the above described main bracket, I employ an auxiliary bracket designated by the reference character B shown in Figures 3 and 4. This auxiliary bracket comprises a pair of arms 8 extending at right angles to each other and provided with adjustable extensions 9. These are formed 110 with slots 10 through which freely work bolts 11, so that by loosening the bolts the

members 9 may be adjusted longitudinally of the arms 8, and by tightening the bolts may be clamped in adjusted position. In order to hold the members 8 and 9 in rigid alignment, they are provided with an interlocking tongue or flange 8^a, as shown in Figure 3. Preferably the extreme ends of the members 9 are enlarged or flattened, as shown at 12, in order to provide an extended bearing surface. At the junction of the arms 8 is a mast receiving socket 13 provided with a set screw 14.

In the actual installation of a mast according to the present invention I proceed as follows. I first insert the mast through the socket 6 in the main bracket A and then insert its lower end through the socket 13 in the lower or auxiliary bracket B and secure such lower bracket rigidly to the mast by means 20 of the set screw 14. The two brackets are then adjusted until they will just snugly fit within the chimney flue and the mast with the bracket B attached is then lowered into the flue. Meanwhile the upper bracket A is seated on the upper end of the flue, as clearly shown in Figure 5, the flange 1 resting upon the top of the chimney and the flange 2 fitting within the flue opening and substantially engaging the side walls thereof at 30 several points. The lowering of the mast is continued until the bracket B is positioned at a considerable distance below the chimney top, a distance of two or three feet having been found satisfactory. After the mast 35 has been lowered to the desired point, it is then clamped in position by tightening up the set screw 7 carried by the bracket A.

It will be observed that by virtue of my improved construction the mast is rigidly held in upright position, being braced or anchored at two widely separated points. It will be further noted that although the mast is strongly and rigidly clamped to the chimney there is no undue strain imposed 45 upon the chimney at any one point, and it will be especially apparent that the load is distributed around and over the entire chimney top where the bricks are sometimes apt to be loose. My improved bracket A, resting 50 as it does upon the topmost bricks and fitting within the flue, tends to retain the upper bricks in position and to strengthen and reinforce the chimney top. At the same time, by reference to Figure 1 it will be seen 55 that the flue opening is restricted or obstructed to only a negligible extent.

As for the lower bracket, the arms 8 bear against two adjacent walls, while the bearing surfaces 12 at the ends of these arms 60 substantially engage the other two walls, thus positively preventing movement of this bracket in any direction. It will be further observed that this lower bracket B is carried and supported wholly by the mast itself, the 65 two brackets being connected only by the

mast. Thus the brackets may be set at any desired distance apart as conditions may require.

The mast C may be of any suitable height, such as six to ten feet, and carries at its top 70 a flange fitting D provided with one or more holes to which the usual insulator carrying the aerial E may be attached. It will be observed that this aerial may extend in any desired direction since the mast is capable of 75 resisting strain equally well in all directions.

Under some conditions, where the aerial is attached at its other end to a tree, pole or other support of sufficient height, the mast C may be made very short, and indeed, 80 may in some instances, be a mere stub, serving only to afford an anchorage. In some cases, the lower bracket B may be unnecessary, but the characteristic advantage of my invention will nevertheless be present, 85 namely, the distribution of the strain over the whole chimney top.

Instead of clamping the mast to the upper bracket by means of the set screw 7, as shown in Figures 1 to 5, I may construct the 90 mast to slide freely through the socket 6 and hold it in the desired vertical position by means of an adjustable collar 15 held in position by a set screw 15^a (see Figure 5^a), 95 which collar simply rests upon the socket 6.

In some cases where the chimney top is constructed of tile or is otherwise of accurate standard dimensions, a one-piece bracket comprising an integral cast metal frame A', 100 as shown in Figures 6 and 7, may be employed in place of the expandable frame illustrated in Figures 1 and 2.

While I have so far illustrated and described means for supporting a mast inside of a chimney flue, the same general principle 105 may be employed for mounting the mast on the outside of the chimney if so desired. This is shown in Figures 8, 9 and 10. In these figures I have illustrated an adjustable or expandable rectangular frame similar to that shown in Figure 1, but comprising sections a', b', c', d', each formed of a horizontal flange 1' and a vertical flange 2', such vertical flange in this case being at the outer 110 edge of the frame and adapted to fit over the outside walls of the chimney top. The mast receiving socket 16 projects outwardly from the frame, preferably at one corner thereof, and is provided with a set screw 17.

The lower or auxiliary bracket corresponding with this arrangement is shown in Figure 10 and consists of a pair of arms 18 provided with extensions 19, formed with slots 20 working over clamping bolts 21. The extreme ends of the extensions 19 are 125 bent at right angles, as shown at 22, and are equipped with pointed clamping screws 22^a adapted to bite into the side walls of the chimney, as will be obvious. A mast receiving socket 23 provided with a set screw 24 130

is formed at the junction of the arms 18 and lies immediately beneath the socket 16. It is thought that the method of applying these brackets will be obvious without further discussion.

While in the previous figures I have shown and described a supporting bracket adapted to rest upon the top of a chimney, I consider it within the spirit of my invention to employ supporting brackets which engage the side walls of the chimney only, without resting upon the top thereof. This is shown in Figures 11 to 13 inclusive. In these figures the upper bracket comprises a hoop or band composed of a pair of opposed U-shaped members 25 and 26 arranged with their ends slotted and overlapping so as to be adjustable, and secured together by means of clamping bolts 27. This band is adapted to encircle the chimney at any desired point, and is held in position by means of a plurality of pointed set screws 28, four of such screws being shown. To one side of the band, as for example, to the member 25, is secured a mast receiving socket 29 equipped with a set screw 30.

The lower bracket 31 is of somewhat similar construction, but does not necessarily encircle the chimney. As shown in Figure 13 this lower bracket comprises simply a U-shaped member having its ends 32 bent at right angles and provided with pointed set screw 32^a adapted to bite into opposite side walls of the chimney. It carries a mast receiving socket 33 provided with a set screw 34.

In all of the modifications herein illustrated and described it will be seen that the mast is supported on the chimney by means of the independent brackets at two widely separated points, thus insuring sufficient strength and rigidity to withstand all strains to which it may be subjected.

While I have illustrated the angular bracket members shown in Figures 1 to 9, inclusive, as formed of cast iron or the like, I also contemplate, as within the scope of my invention, forming these brackets from sheet or wrought metal bent or pressed into shape. It may be stated, however, that the heavier these brackets are, the better they will function, since the weight tends to increase the stability of the structure.

What I claim is:

1. The combination with a mast, of a bracket attached to and extending at right angles to said mast, a second bracket extending parallel with the first but spaced therefrom, said second bracket being secured directly to and carried wholly by the lower end of said mast, and said brackets being adapted to engage the side walls of a vertical structure at separated points thereof to rigidly support the mast.

2. The combination with a mast, of a bracket attached to and extending at right angles to said mast, said bracket comprising two portions at substantial right angles to each other, a second bracket having portions extending respectively parallel with those of the first, but spaced therefrom, said second bracket being secured directly to and carried wholly by said mast, and said brackets being adapted to engage the side walls of a rectangular vertical structure at separated points thereof to support the mast.

3. The combination with a mast, of means for mounting the same inside of a vertical hollow structure, without substantially restricting the interior thereof, said means comprising a pair of mast supporting arms extending horizontally from the mast, said arms lying in the same plane but disposed at an angle to each other and adapted to rest upon the top of such structure, and a second member adapted to engage the side walls thereof at a plurality of separated points, and carried wholly by the lower end of said mast.

4. The combination with a mast, of a bracket therefor comprising a socket, and a pair of arms extending from said socket at right angles to each other and to the mast, each arm being L-shaped in cross-section and adapted to engage the top and side wall of a vertical structure, and a second bracket also comprising a mast receiving socket and a pair of arms extending parallel with those of the first bracket, and adapted to engage the side walls of the vertical structure, said second bracket being secured to the mast at a point below the first.

5. A mast holder for chimneys comprising a bracket having a socket to receive the mast, and a pair of arms extending from said socket at right angles to each other, each of said arms having a horizontal portion to rest on the top of the chimney, and a vertical portion to engage the inside wall thereof.

6. A mast holder for chimneys comprising an open frame adapted to fit within and engage the side walls of the chimney flue, said frame having a horizontal portion adapted to rest upon the top of the chimney, and a mast receiving socket carried by said frame adjacent one side thereof.

7. A device for supporting a wire from a chimney or the like, comprising an angular frame constructed to rest on the top edge of the chimney and engage two adjacent side walls thereof substantially throughout their length, whereby the strain is distributed over a large area, and wire anchoring means carried by said frame.

In testimony whereof I affix my signature.

EMANUEL INGHAM.
